UNITED STATES PATENT OFFICE.

JOSÉ GARCIA HERNANDEZ, OF HAVANA, CUBA.

MACHINE FOR DECORTICATING FIBROUS PLANTS.

SPECIFICATION forming part of Letters Patent No. 447,152, dated February 24, 1891.

Application filed May 2, 1890. Serial No. 350,374. (No model.)

To all whom it may concern:

Be it known that I, JOSÉ GARCIA HERNANDEZ, of Havana, Cuba, have invented a new and Improved Machine for Decorticating Fibrous Plants, of which the following is a full, clear, and exact description.

The object of the invention is to provide a new and improved decorticating machine which is simple and durable in construction, 10 very effective in operation, and adapted for breaking ramie, jute, hemp, or other similar fibrous plants in such a manner that the fiber is left clean of any ligneous or woody matter, and at the same time the fiber is rendered 15 very smooth, the exterior pelicle or film being to a great extent removed.

The invention consists of a reciprocating double knife operating in conjunction with a fixed and a yieldingly-mounted presser-bar.

20 The invention also consists in certain parts and details and combinations of the same, as will be described hereinafter, and then pointed out in the claims.

Reference is to be had to the accompanying 25 drawings, forming a part of this specification, in which similar letters of reference indicate corresponding parts in all the figures.

Figure 1 is a front view of my improved machine with parts broken out. Fig. 2 is a 30 sectional side elevation of the same on the line xx of Fig. 1. Fig. 3 is a side elevation of the mechanism for actuating the feeding devices. Fig. 4 is a face view of a modified form of the cam for operating the yielding 35 presser-bar, and Fig. 5 is an enlarged sectional side elevation of part of the improvement.

The improved decorticating-machine is provided with a suitably-constructed frame A, supporting in its rear a table B, on which the 40 material to be treated is placed to be fed to the feeding-rollers C and D, arranged one above the other and at the front end of the said table B. The feeding-rollers C and D are journaled in the sides of the main frame 45 A and are connected with each other by gear-wheels E and E', so that when a rotary motion is imparted to one of the rollers the other rotates with it.

On the outer end of the lower roller C is arranged a ratchet-wheel F, engaged by a spring-

pressed pawl G, pivoted on a lever H, loosely fulcrumed on the shaft of the said roller C. The outer end of lever H has a lengthwise slot H'. An arm J is fixed on one end of the shaft K, which has its bearings in the upper part 55 of frame A. The arm J is likewise provided with a slot J' and is connected by a bolt or pin I with said lever H, as shown—that is to say, the bolt I is clamped by a nut at any desired point in the slot of arm J and slides 60 freely in the slot of lever H. It is therefore a crank or wrist pin for the latter. The shaft K has a fast pulley K' and loose pulley K², respectively, connected in the usual manner with suitable machinery for imparting a rotary 65 motion to the said driving-shaft K. On the latter is also secured a suitable fly-wheel K³.

When the shaft K is rotated, the arm J imparts a swinging motion to the lever H, which in its forward stroke imparts, by the pawl G, 70 motion to the ratchet-wheel F, and consequently to the feed-roller C, which operates the other feed-roller D. On the return-stroke of the lever H the two feed-rollers remain stationary. The throw given by the pawl G to 75 the ratchet-wheel F can be varied by adjusting the pivot-pin I in the slot J' of the arm J, so that the material may be fed a greater or less distance, as desired. On the main driving-shaft K are also arranged the crank-arms 80 K⁴, pivotally connected with links L, extending downward and pivotally connected with a rectangular frame N, having its ends fitted to slide vertically in slots A', arranged in the sides of the main frame A. On the top and 85 the bottom bars of the rectangular frame N are secured the knives O and O', held transversely adjustable on the side bars by means of screws, as shown. The knives O and O' have opposite cutting-edges, as is plainly 90 shown in Fig. 2, the bevel of the cutting-edge of the knife O extending upward, while that of the other knife O' extends downward, as is plainly shown in Fig. 2.

In the rear of the frame N and its knives 95 O and O' is arranged a transversely-extending fixed presser-bar P, located in front of the roller C, and having its top about in line with the top of the table B and the roller C. Above this fixed presser-bar P is arranged a movable 100

presser-bar Q, similar in shape to the fixed presser-bar and provided on its ends with upwardly-extending arms Q', fitted against the inner surfaces of the sides of the main frame 5 A, and each provided with vertically-arranged slots Q², through which pass bolts Q³, screwing in the sides of the main frame.

On the upper end of each arm Q' is arranged a projection Q⁴, adapted to be engaged 10 by a cam R, which may be single, as shown in Fig. 2, or double, as illustrated in Fig. 4, the said cam being secured on the driving-shaft K. Against the under side of each arm Q' presses a coiled spring Q⁵, coiled around 15 the rod Q⁶, extending from the arm Q' downward through a suitable bearing Q⁷, formed on each of the sides of the main frame A. The springs Q⁵ serve to hold the presser-bar Q in an uppermost position, the upward move- 20 ment being limited by the arms Q' resting against the peripheries of the cams R. When the main shaft K is rotated, the said cams R, acting on the arms Q', press the latter downward, and consequently impart a vertical 25 sliding motion to the presser-bar Q, being vertically guided by the bolts Q³ passing through the slots Q² of the said arms Q', supporting the said presser-bar.

Above the table B is arranged a transverse 30 board S slightly inclined and serving to prevent the material from passing over the roller D. The presser-bar P serves also as a guide to the roller C in order to prevent the material from taking any other direction than that con- 35 ducting directly to the knives; and as the presser-bar Q is movable its thickness will be reduced somewhat, so as to adapt a fixed guide T (see Fig. 5) between the same and the rollers C and D, in order to force the material 40 to take its way right through the knives.

The operation is as follows: When the main driving-shaft K is set in motion, a reciprocating motion is imparted to the knives O and O', held in the knife-frame N so that the cutting-edges of the two knives alternately pass 45 the opening made between the presser-bars P and Q. The ramie, jute, hemp, or other analogous material is placed by the operator on the table B and shoved between the two rollers 50 C and D, which on the forward stroke of the lever H are rotated to feed the material between and past the presser-bars P and Q into the opening formed between the two knives O and O'. When the lever H is on the re- 55 turn-stroke, the feeding ceases, and then the cams R press the presser Q downward onto the material so as to clamp the latter in place. Then the knife O descends, and by its cutting-edge passing onto the material breaks the lat- 60 ter, and at the upward stroke the lower knife O' acts against the under side of the material and cleans the latter from the woody portion broken by the knife O. When the knife-frame N again commences to move downward 65 and the presser Q is in its uppermost position, caused by the action of the springs Q⁵, then the lever II is on its forward stroke and

turns the rollers C and D so as to feed the material forward again. As soon as the lever H commences its return-stroke the movable 70 presser-bar Q clamps the material again and the knives O and O' operate on the material on the downward and upward stroke, as previously described.

It will be seen that as the decorticated portion of the material when passing out of the machine is resting on the dull edge of the lower knife O', while the remainder portion of the material is not yet broken, but clamped by the bars P and Q and the rollers C and D, 80 the ligneous part, that although loosened could perhaps still remain mingled within the decorticated part of the material, is separated by the friction and agitation of the reciprocating knives O and O' in their rapid up-and-down movement.

The rollers C and D are made smooth, and are preferably of rubber, so as not to press or break the material, thereby preventing the woody portions from becoming like leather 90 and less breakable after being crushed, as is the case in machines as at present constructed.

The limit attained by both the cutting-edges of the knives O and O' on their upward and downward strokes, respectively, in passing the front faces of the bars P and Q should not be less than the forward movement of the material, so that the knives in passing the bars strip off by friction the pellicle. The knives O and O' are transversely adjustable 100 in order to be enabled to graduate, as needed, the space between the knives and the front faces of the bars P and Q without touching the frame N, thus being able to adjust the same in case the space should be too narrow 105 and in breaking the ligneous part to avoid also the cutting of the fiber. By removing the transversely-adjustable knives O and O' on frame N they can be exactly graduated, 110 so as to break indefinitely the ligneous part, preventing at the same time its interference 115 between the knives O and O' and the faces of the bars P and Q.

It will be seen that this machine is very simple in construction and dispenses with all 115 grooved rollers and breakers previously employed in machines of this kind. In breaking the material in small fragments this machine not only leaves the fiber clean of the ligneous parts and to a great extent without the exterior pellicle, but also works as a cleaning and smoothing machine for the fibers, which when dried are preferably passed through the machine a second time, so as to obtain a first-class product.

In this machine the material may be fed to the rollers C and D with the leaves and buds on, thus dispensing with the difficult and expensive operation of stripping off the leaves previous to passing the material into the machine.

It will further be understood that there is no loss of material whatever, as all the stems of all sizes must infallibly pass between the

rollers C and D to the bars P and Q and the knives O and O' to be treated, as above described.

It will further be seen that the machine operates, no matter in which direction the shaft K is rotated. By this machine the drying of the fibers is facilitated on account of the removal of the pellicle, as in this way the fiber is more directly exposed to the influence of the drier.

Having thus described my invention, what I claim as new, and desire to secure by Letters Patent, is—

1. In a decorticating-machine, the combination, with reciprocating double knives, of a fixed presser-bar and a movable presser-bar arranged in the rear of the said knives and in line with the same, and means for operating said bar, substantially as shown and described.

2. In a decorticating-machine, the combination, with reciprocating double knives, of a fixed presser-bar and a movable presser-bar arranged in the rear of the said knives and in line with the same, and means for operating said bar, and feed-rollers having an intermittent rotary motion and serving to feed the material to the said bars and knives, and means for intermittently rotating said rollers, substantially as shown and described.

3. In a decorticating-machine, the combination, with reciprocating double knives, of a fixed presser-bar and a movable presser-bar arranged in the rear of the said knives and in line with the same, feed-rollers having an intermittent rotary motion and serving to feed the material to the said bars and knives, and means, substantially as described, for intermittently rotating said rollers and for imparting motion to the said knives and movable presser-bar, as set forth.

4. In a decorticating-machine, the combination, with a knife-frame having a reciprocating motion and knives secured on opposite bars of the said frame, of a fixed presser-bar arranged in the rear of the said frame in line with the said knives, and a movable presser-

bar arranged above the said fixed presser-bar and adapted to clamp the material on the said fixed presser-bar while the knives operate on the material, and means for operating said bar, substantially as shown and described.

5. In a decorticating-machine, the combination, with a knife-frame having a reciprocating motion and knives secured on opposite bars of the said frame, of a fixed presser-bar arranged in the rear of the said frame in line with the said knives, a movable presser-bar arranged above the said fixed presser-bar and adapted to clamp the material on the said fixed presser-bar while the knives operate on the material, and means, substantially as described, for imparting a reciprocating motion to the said knife-frame and a downward motion to the said movable presser-bar, substantially as shown and described.

6. In a decorticating-machine, the combination, with a knife-frame having a reciprocating motion and knives secured on opposite bars of the said frame, of a fixed presser-bar arranged in the rear of the said frame in line with the said knives, a movable presser-bar arranged above the said fixed presser-bar and adapted to clamp the material on the said fixed presser-bar while the knives operate on the material, means, substantially as described, for imparting a reciprocating motion to the said knife-frame and a downward motion to the said movable presser-bar, and springs for raising the said presser-bar, substantially as shown and described.

7. In a decorticating-machine, the combination, with a fixed presser-bar, of a movable presser-bar having arms guided vertically, springs pressing on the said arms to raise the movable presser-bar, and cams adapted to press on the said arms to lower the said presser-bar, substantially as shown and described.
